UNITED STATES PATENT OFFICE.

JACOB M. HANSEN, OF CHICAGO, ILLINOIS, ASSIGNOR TO HARTMANN-MALCOM CO., OF CHICAGO, ILLINOIS, A CORPORATION OF ILLINOIS.

DESIGN FOR AN ELECTRIC-LAMP STANDARD.

53,396.

Specification for Design.

Patented June 3, 1919.

Application filed February 19, 1919. Serial No. 278,070. Term of patent 14 years.

To all whom it may concern:

Be it known that I, JACOB M. HANSEN, a citizen of the United States, residing at Chicago, in the county of Cook and State of Illinois, have invented a new, original, and ornamental Design for an Electric-Lamp Standard, of which the following is a specification, reference being had to the accompanying drawing, forming part thereof.

Figure 1 is a side elevation of the lamp standard showing my new design;

Copies of this patent may be obtained for five cents each, by addressing the "Commissioner of Patents, Washington, D. C."

Fig. 2 is a transverse section of the standard column.

I claim:

The ornamental design for an electric lamp standard, as shown.

JACOB M. HANSEN.
